UNITED STATES PATENT OFFICE.

JOHNNETA W. WELTON, OF RUTHERFORD, NEW JERSEY.

LUMINOUS PEN OR PENCIL.

1,304,131.

Specification of Letters Patent.

Patented May 20, 1919.

Application filed July 24, 1918. Serial No. 246,463.

To all whom it may concern:

Be it known that I, JOHNNETA W. WELTON, a citizen of the United States, residing at No. 78 Lincoln avenue, Rutherford, Bergen county, State of New Jersey, have invented a certain new and useful Improvement in Luminous Pens or Pencils, of which the following description, in connection with the accompanying drawings, is a specification, like characters on the drawings representing like parts.

This invention relates to luminous fountain pens and pencils.

The primary object of my invention is to provide a fountain pen or pencil containing, movably attached within the body thereof, a small electric illuminator which can be readily raised so that the illuminator is brought without the barrel or body of the fountain pen or pencil, whereby it may be used for diffusing light upon a pad or paper by doctors and nurses when writing prescriptions or reports in the sick room, and the like, and by military officers in the field when a ready at hand subdued light is required, and other illumination difficult or impossible.

A further object is to provide a small portable pocket electric illuminator for use by doctors and surgeons for diagnostical purposes, and as an emergency light in rendering first aid and performing minor operations in the field where other illumination is not at hand or difficult.

35 A further object is to provide a small portable pocket electric illuminator for use by autoists as a miniature trouble light.

In the accompanying drawings:

Figure 1 is a side elevation of the device with a portion of the side broken away, showing the hinged socket, electric bulb, insulated contact wire, insulated contact switch, and wires for connecting to a battery.

45 Fig. 2 is a side elevation of the device with a portion broken away, showing the hinged socket raised into position, for giving illumination, and showing also the electric bulb and insulated contact wire, with one end resting within and against the insulated contact switch, and a portion of the wires connecting the device to a battery.

50 Fig. 3 is a side elevation in section of a portion of the end of the pen or pencil, the insulation, the contact switch, and the pri-

mary and secondary wires for connecting the device to a battery.

Fig. 4 is a side elevation of a portion of the hinged socket, showing its construction in detail, and showing a portion of the insulated contact wires gripped therein.

In the drawings, the numeral 1 indicates the main member or barrel of the fountain pen or pencil, which is constructed of brass or other suitable material. Numeral 2 represents the hinged socket member. Numeral 3 represents the contact wire insulation. Numeral 4 represents the contact wire. Numeral 5 represents the switch insulation. Numeral 6 represents the cylindrical cupped switch. Numerals 7 and 8 represent the electric wires. Numeral 9 represents the rivet which connects the socket member to the barrel member. Numeral 16 represents the wire insulation and covering. Numeral 10 represents the electric bulb or illuminator. Numeral 11 represents the portion of the socket which fits and closes the opening into the barrel of the pen or pencil when the device is closed. Numeral 12 represents the dovetail joint or formation in the barrel or case, which seats and retains the end of the pen or pencil containing the cylindrical contact switch. Numeral 13 represents one contact end of the insulated contact wire. Numeral 14 represents the other end of the insulated contact wire. Numeral 15 represents the bull's-eye illuminating end of the electric bulb from which the light is emitted when in use. Numeral 17 represents the tapering end of the pen or pencil. Numeral 18 represents the pen or pencil point. Numeral 19 represents the threaded end of the electric bulb whereby it is retained within the socket. Numeral 20 represents the threaded opening in the socket member wherein the electric bulb is retained. Numeral 21 represents the beveled edge of that portion of the socket member which fills or closes the opening into the pen or pencil case or body. Numeral 22 represents the tongs or cleats formed in the socket member for retaining and securing the insulated contact wire. Numeral 23 indicates a portion of the contact wire with the insulation broken away. Numeral 24 indicates a bend in the socket member. Numeral 25 indicates holes in portions of the socket member bent and formed so as to form a hinge. Numeral 26 indicates the opening in the end of the pen or pencil barrel or case

- for introducing primary and secondary battery wires. Numeral 27 indicates the position at which one of the battery wires is soldered and secured to the end of the barrel or case. Numeral 28 indicates the position at which the remaining battery wire is soldered and secured to the end of the cylindrical cupped contact switch. Numeral 29 indicates the partition which separates the portion of the main barrel or case containing the pencil or fountain pen ink from the rear portion of the barrel which contains the illuminating device. Numeral 30 indicates an oblong opening in the main case or barrel of the pen or pencil, which is adapted to be closed by a portion of the socket member. Numeral 31 indicates a cylindrical cup member forming the rear end of the pen or pencil. Numeral 32 indicates perforated tongs or cleats formed integral with the socket member 2 for attaching the same to the main case hinge fashion, by means of a rivet 9. Numeral 33 represents the retaining ends of the tongs or cleats 22.
- 25 The main barrel or case 1 is preferably formed of cylindrical metal tubing, in one end of which the tapering pen or pencil member 17 is removably attached, and the other end of which is closed by an irremovable tubular cup member 31. An oblong opening 30 is provided in the main barrel or case adapted to be closed by a portion of the socket member, having its end 21 beveled or tapered so as to give purchase with the end 35 of a finger nail when it is desired to raise the socket member and to facilitate which operation a small space 35 is left between the end 21 of the socket member and the main barrel or case of the device.
- 40 When the socket member 2 has been raised into operative position as in Fig. 2, the point or end 13 of the contact wire 4 is brought into contact relation with one side of the cylindrical cupped contact switch 6.
- 45 The rivet 9 passes through the case or barrel near the diameter, and also through the holes 25 or openings in the socket member 2, being at all times in contact with both members.
- 50 The electric bulb engages one end 14 of the contact wire 4 and the outer case 10 of the electric bulb engages at all times the threaded opening 20 of the socket member 2, so that when the socket member is raised into operative position, as indicated in Fig. 2, with the end 13 of the contact wire 4 resting upon the side of the cylindrical switch member 6, and the wires 7 and 8 are attached to a battery in the customary way, the electric circuit is closed and electric current is imparted to the electric bulb whereby it is caused to glow and emit light as indicated.
- 65 It will be noted by this arrangement of parts that the mere raising of the socket

member 2, as indicated in Fig. 2, closes the contact and throws on the electric current and by merely lowering the socket member 2 into the main barrel or case of the device, the end of the contact wire 13 is raised from contact with the cylindrical switch member 6, whereby the circuit is opened and the contact broken and the electric current cut off.

It will also be noted that the insulation 3 of the contact wire prevents the contact wire 75 from touching the socket member 2 and the insulation 5 prevents the tubular contact switch member 6 from touching the end member of the case 31.

As will be seen from the drawings, the wires 7 and 8 are introduced into the end 80 of the case member 31 through a suitable opening 26 provided therein.

In practice the socket member 2 is preferably formed of one piece of suitable metal 85 having three tongs or cleats on each side, the end cleats 32 capable of being bent at right angles forming a hinge, and the tongs or cleats 22 bent at right angles with the ends 33 bent down over the insulation 3 so as to 90 firmly grip and retain the same, and the other end of the socket member 2, is formed loop fashion, and bent upon itself at 24 as in Fig. 3, a portion thereof, 11, having cylindrical formation longitudinally describing 95 a section of the main body member, and adapted to operate in the opening therein freely so that when the member is closed, as in Fig. 1, with the under portion resting upon the inner wall of the main case, it completely closes the opening 30 in the main member, except for the small space at one end 35, so that the outer surface of the device is substantially uniform.

The circumference of the end of the main 105 case is uniformly reduced dovetail fashioned at 12 the thickness of the wall of the main case, for the purpose of seating the end portion 31, the edge of which, when in place, is knurled or otherwise slightly depressed so as to firmly and permanently grip and close the end of the main case 1.

The circular disk or partition 29 made of metal, rubber or other suitable material, is irremovably introduced and sealed in the 115 barrel of the main case before assembling, whereby the front portion or end of the main case is tightly sealed and suitable for retaining ink or other fluid.

It will be noted that in this device the 120 need for throwing on current by the battery case switch, in the customary way, is obviated, and for a device of this description desirable to be carried in the pocket where a pocket clip is not desirable or adaptable, 125 this device offers unusual features, that cannot readily be made available in any other way.

It will also be understood that the end 17 may be formed so as to employ any stand- 130

ard, usable, permissible and adjustable lead pencil device or permissible fountain pen device, so that the main device may be made either to be used as an illuminated pen or 5 as an illuminated lead pencil.

Having thus described my said improvement, I claim as my invention and desire to secure by Letters Patent under this specification:

- 10 1. A tubular casing adapted to hold a pen or pencil having an opening in the body thereof, an electric bulb attached within the opening hinge fashion, capable of being raised or moved to a position outside the said opening, suitable wire or metal connections for attaching the tubular casing to an electric battery whereby electric current may be imparted to the electric bulb so as to cause it to glow and impart light.
- 15 2. A tubular casing adapted to hold a pen or pencil having an opening in the body thereof, an electric bulb attached within the body, hinge fashion, capable of being raised or moved to a position outside the said opening, a contact switch adapted to be engaged and closed by the raising of the electric bulb and opened by the lowering of the electric bulb, suitable wire or metal connections for attaching the tubular casing to an electric battery whereby electric current may be imparted to the electric bulb so as to cause it to glow and emit light for illuminating purposes.
- 20 3. A tubular casing adapted to hold a pen or pencil, having a recess in the body there-

of, a hinged socket member movably attached therein, adapted for holding a small electric light bulb, and formed to close the opening in the main member, insulated wire means and switch contact means suitable 40 for conveying electric current.

4. A tubular casing adapted to hold a pen or pencil, having within a recess therein a small electric bulb, hinged socket means with screw means for retaining the electric 45 bulb, movably attached within the body recess so that it may be raised to a position without the casing for imparting light, pivot means for holding the socket means, insulated wire means attached to the socket 50 means for conveying electric current to the electric bulb.

5. The combination of a tubular casing, adapted to hold a pen, an ink chamber and tubular means extending therefrom to the 55 pen for supplying ink thereto, a socket for holding an electric bulb, movably retained within a recess in the casing, insulated electric switch means at one end of the casing, suitable insulated wires for supplying electric current from a battery to the electric bulb, all substantially as described and illustrated in the drawing.

In testimony whereof I have signed my name to this specification in the presence of 65 two subscribing witnesses.

JOHNNETA W. WELTON.
